W. J. HEINTZ.

PAPER HOLDER.

APPLICATION FILED OCT. 27, 1919.

1,370,314.

Patented Mar. 1, 1921.

INVENTOR.

WILLIAM J. HEINTZ

BY

Thomas L. Wilder

ATTORNEY.

UNITED STATES PATENT OFFICE.

WILLIAM J. HEINTZ, OF UTICA, NEW YORK.

PAPER-HOLDER.

1,370,314.

Specification of Letters Patent.

Patented Mar. 1, 1921.

Application filed October 27, 1919. Serial No. 333,481.

To all whom it may concern:

Be it known that I, Dr. WILLIAM J. HEINTZ, a citizen of the United States, residing at Utica, in the county of Oneida and State of New York, have invented certain new and useful Improvements in Paper-Holders, of which the following is a specification, reference being had therein to the accompanying drawing.

10 My invention relates to a paper holder and I declare the following to be a full, clear, concise and exact description thereof sufficient to enable anyone skilled in the art to which it appertains to make and use the 15 same, reference being had to the accompanying drawings in which like reference characters refer to like parts throughout the specification.

The object of the invention is to provide 20 a device for holding sheets of paper temporarily upon the padded part of a sectional head rest for dental or other like chairs. The paper holder is designed to improve upon the patent to Elias G. Dayeh, No. 25 1,245,322 granted Nov. 6, 1917. Furthermore, it permits the user to replace quickly a new sheet of paper upon the padded part of the sectional head rest each time a person occupies the chair, whereby said pad will 30 present a sanitary surface for resting said person's head.

The object will be understood by referring to the drawings, in which:

Figure 1 is a perspective view of one of 35 the pads of a sectional head rest, showing the paper holder attached and the sheet of paper in position;

Fig. 2 is a bottom plan view of the pad shown in Fig. 1;

Fig. 3 is a detail enlarged view in fragment of a ring employed;

Fig. 4 is a detail view, showing a perspective of the paper holder attachment;

Fig. 5 is a detail enlarged view, showing 45 a perspective of a hinge and paper lock employed;

Fig. 6 is a bottom plan view of the pad illustrated in Fig. 1 with the paper holder attached and certain other parts removed.

50 Referring more particularly to the drawings, the pad of a sectional head rest of a dental or other like chair is represented by —1— and rests upon a plate 2 which has an aperture at 3 for the projection therethrough of a hollow internally screw threaded tube 4 that is fulcrumed upon gudgeons 5—5

formed integral with the metal pad frame 6. Between the metal pad frame 6 and the plate 2 is disposed the leaf 7 of a hinge, which leaf 7 has an aperture 8. The aperture 8 is brought into alinement, when assembling the parts, with a corresponding aperture in the plate 2 and an internally threaded aperture 9 in the frame 6, and a screw bolt 10 disposed through said apertures to hold the parts together in assembled position.

The leaf 7 has an upstanding part 11 that is split from its top edge downward a short distance to form a tongue 12. The tongue 12 is bent over, as clearly shown in Fig. 4, whereby to form one element of a lock to be hereinafter described.

The lower portion of the part 11 is cut also to provide another tongue 15 that is bent round to embrace the pivot pin 16 of the hinge.

A second leaf 17 has a recess cut therein to form two free ends or tongues 18—18 that are bent round to engage the pin 16 on opposite sides of the tongue 15. The opposite end of the leaf 17 is split to form three free ends or tongues 22—22 and 23 that are bent round to engage the contiguous part of a metal ring 20. The ring 20 is reduced at 21—21 to provide bearings for the tongues 22—22, disposed on either side of the tongue 23, whereby to hold the leaf 17 and connected parts in given location relative to the metal ring 20. The middle tongue 23 rests upon the enlarged center part 24 of the ring 20. The free end of said tongue 23 extends straight down a short distance, whereby to form a locking member 25, under which the upper surface of the tongue 12 of the leaf 7 snaps to hold the contiguous edge of the paper sheet 26 therebetween. The ring 20 is adapted to fit rather snugly around the periphery of the pad —1—.

In order to replace a paper sheet 26 upon the pad —1—, the user of the chair, grasps manually the ring 20 diametrically opposite the location of the hinge and raises said ring off the pad —1— and throws it back into the position shown in Fig. 4, whereby to unlock the leaf 17 from the leaf 7, or to disengage the tongue 12 from the locking member 25. He then casts aside the old sheet of paper 26 and replaces it with a new sheet 26. When returning the ring 20 to original position about the periphery of the pad —1—, the tongue 12 will snap under the locking

member 25, thereby engaging the contiguous edge of a sheet of paper 26, which has been inserted therebetween and also closing the free edge or periphery of the sheet about 5 the periphery of the pad —1— as illustrated in Fig. 1.

Having thus described my invention what I claim as new and desire to secure by Letters Patent is:

10 1. In a paper holder for dental or like chairs, means for securing a sheet of paper in place upon the pad of the head rest of said chair, a hinge for securing said means in said head rest, and means for locking the 15 parts of said hinge together, whereby to grip the edge of said sheet of paper.

2. In a paper holder for dental or like chairs, means for securing a sheet of paper in place upon the pad of said chair, and a 20 hinge for holding said means in place to said pad, said hinge having a tongue adapted to lock the parts of said hinge together, whereby to grip the edge of said sheet of paper.

3. In a paper holder for dental or like chairs, a metallic ring adapted to embrace 25 the periphery of the padded head rest of said chair, a hinge for holding said ring to said pad, a tongue on one part of said hinge adapted to lock with a tongue on another part of said hinge, whereby to grip the edge 30 of said sheet of paper therebetween.

4. In a paper holder for dental or like chairs, a pad, a hinge carrying paper holding means, and other means for locking the parts of said hinge together, whereby to grip 35 the edge of the paper to aid in holding the same upon said pad of the chair.

5. In a paper holder for dental or like chairs, a pad, a hinge carrying a ring, and tongues on said hinge for locking the parts 40 of said hinge together, whereby to grip the edge of the paper to aid in holding the same upon the head rest pad of said chair.

In testimony whereof I have affixed my signature.

WILLIAM J. HEINTZ.
